UNITED STATES PATENT OFFICE.

EVELYN LEISS, OF BRONXVILLE, NEW YORK.

EGG-TESTER.

942,652.

Specification of Letters Patent. Patented Dec. 7, 1909.

Application filed June 19, 1909. Serial No. 503,185.

To all whom it may concern:

Be it known that I, EVELYN LEISS, a citizen of the United States, and a resident of Bronxville, in the county of Westchester 5 and State of New York, have invented a new and Improved Egg-Tester, of which the following is a full, clear, and exact description.

The invention is an improvement in egg 10 testers and has in view a device of this character in which the eggs may be conveniently inspected at the outside of the usual egg-testing box.

To this end the invention in general consists of a box having egg-seating openings 15 in the top and provided at the side with a door having a mirror on its inner face, the door being hinged to swing downwardly and outwardly to a position to reflect the light 20 passing through the openings.

Reference is to be had to the accompanying drawings forming a part of this specification, in which similar characters of reference indicate corresponding parts in all 25 the views.

Figure 1 is a perspective view of an egg tester constructed in accordance with my invention; Fig. 2 is a longitudinal vertical section of the same substantially on the line 30 2—2 of Fig. 3; and Fig. 3 is a cross-section of the tester.

The egg tester essentially consists of a box 5 having one or more egg-seating openings 6 in the top and provided with a mirror 7 movable to a position at the outside of the box to reflect the light passing through the openings. I preferably construct the box of sheet metal, the body of which is made of a one-piece blank. The blank is 10 bent upon itself to form outwardly-extending flanges 8 at each side of the top of the box, and from one of these flanges the blank is turned downwardly to form the upper portion of one of the sides 9, the opposite 15 side of the box being likewise formed from the blank but continuous in height and width with the bottom 10, the blank at the side edge of the bottom directly below the side 9 being turned inwardly to form a diagonal wall 11. The end portions of the blank are integral with the bottom 10 and are flanged and turned upwardly into engagement with the sides and top.

The opening in the side of the box left below the side wall 9 is normally closed by a

door 12 hinged at its lower edge at the junction of the bottom 10 and diagonal wall 11, the door having the metal of which it is constructed turned inwardly at each end to form ways 13 which are open at the top of 60 the door to slidably receive the mirror 7, this construction enabling the mirror to be easily renewed should it be broken or otherwise rendered unfit for use. A cover 14, also of sheet metal, is inwardly turned at the opposite side edges to form ways 15 arranged to slidably receive the outwardly-projecting flanges 8 of the box, the cover serving to close such egg-seating openings 6 in the top of the box as are not in use, thus excluding 65 all light from the top except such as passes through the egg. The inner side of the side wall 10 and the top of the box, as also the upper face of the wall 11, will ordinarily be blackened to absorb the light so that when 70 the mirror is turned down to the inclined position shown in Fig. 1, the uncovered openings in the top of the box will be plainly visible in the mirror, making it unnecessary to look inside of the box in determining the 75 condition of the eggs.

Having thus described my invention, I claim as new and desire to secure by Letters Patent:

1. In an egg tester, a box having an egg- 85 seating opening in the top and having a door at one side hinged at its lower edge to swing outwardly, and a mirror carried on the inner face of the door, through which the said opening is observable when the door 90 is opened.

2. In an egg tester, a box having egg-seating openings in the top and provided with a door at one side hinged at its lower edge to swing outwardly, a wall in the box 95 inclining downwardly toward the door, and a mirror arranged on the inner side of the door.

3. In an egg tester, a box having egg-seating openings in the top, a door arranged 100 at one side of the box hinged to swing downwardly and outwardly, and a mirror through which the openings are observable, removably held on the inner face of the door.

4. In an egg tester, a box having egg-seating openings at the top and provided with a side portion extending from the top, a door hinged at its lower edge to swing 110 downwardly and outwardly and closing an

opening under the said side portion of the box, a wall arranged in the box inclining downwardly to the lower edge of the door, and a mirror through which the openings 5 in the top of the box are observable when the door is open, carried on the inner side of the door.

In testimony whereof I have signed my name to this specification in the presence of two subscribing witnesses.

EVELYN LEISS.
